(57) **CLAIM**

We claim the ornamental design for the sofa, as shown and described.

DESCRIPTION

FIG. 1 is a top, perspective view of a sofa comprising the present invention.

FIG. 2 is a front elevational view of the sofa shown in FIG. 1.

FIG. 3 is a side elevational view of the sofa shown in FIGS. 1 and 2.

FIG. 4 is a side elevational view of the sofa shown in FIGS. 1, 2, and 3.

FIG. 5 is a rear elevational view of the sofa shown in FIGS. 1, 2, 3, and 4.

FIG. 6 is a top plan view of the sofa shown in FIGS. 1, 2, 3, 4, and 5.

FIG. 7 is a bottom plan view of the sofa shown in FIGS. 1, 2, 3, 4, 5, and 6.

FIG. 8 is a perspective view of another embodiment of sofa comprising the present invention.

FIG. 9 is a front elevational view of the sofa shown in FIG. 8.

FIG. 10 is a side elevational view of the sofa shown in FIGS. 8 and 9.

FIG. 11 is a side elevational view of the sofa shown in FIGS. 8, 9, and 10.

FIG. 12 is a rear elevational view of the sofa shown in FIGS. 8, 9, 10, and 11.

FIG. 13 is a top plan view of the sofa shown in FIGS. 8, 9, 10, 11, and 12; and,

FIG. 14 is a bottom plan elevational view of the sofa shown in FIGS. 8, 9, 10, 11, 12, and 13.

The broken lines are for environmental purposes only and form no part of the claimed design.

1 Claim, 12 Drawing Sheets
